UNITED STATES PATENT OFFICE.

JOHN M. MCNEAL AND WILLIAM F. RUNNELLS, OF RICE'S, MINNESOTA.

MECHANICAL MOVEMENT.

SPECIFICATION forming part of Letters Patent No. 432,192, dated July 15, 1890.

Application filed August 2, 1889. Serial No. 319,569. (No model.)

To all whom it may concern:

Be it known that we, JOHN M. MCNEAL and WILLIAM F. RUNNELLS, citizens of the United States, residing at Rice's, in the county of Benton, State of Minnesota, have invented certain new and useful Improvements in Mechanical Movements, of which the following is a specification, reference being had therein to the accompanying drawings.

10 Our invention relates to improvements in devices for converting from a distance more or less remote reciprocating into rotary motion; and the objects of our improvement are to provide at a small cost a device of this nature and adapt it to operate a churn, washing-machine, or other mechanism for domestic and other purposes. We attain these objects by the construction illustrated in the accompanying drawings, in which—

20 Figure 1 is a perspective view of the device constructed in accordance with our invention. Fig. 2 is a side view of the operating ratchet-wheel and its pawls connected with the sprocket-wheel of the device.

25 In said drawings, A represents a pump-rod—as, for example, the vertical rod that is usually connected with the crank of a windmill-shaft and receives therefrom a vertically-reciprocating motion, said rod being

30 guided at the bottom either by the pump-barrel or by the standard B, having the rod-guides b. To the pump-rod A is pivoted at a the upper end of a pitman C, having its lower end pivoted to the outer end of T-shaped

35 arm D, the head or perpendicular portion of which is attached to the middle portion of the oscillating double-lever bar E, that is pivoted at e to the stanchion F, the pivot having its opposite end supported by the iron brace f, secured to the horizontal beam F², forming a

40 part of the stanchion-supporting frame. The ends of the double lever E are connected on one side with the free end of the arm D by means of bracing-rods d, and on the opposite

45 side with wires G, that are converging toward a sprocket-wheel H, loosely mounted on a shaft I, carried in bearings k, attached to stanchions K at a more or less remote distance

from the stanchion F, or from the pump-rod A of the windmill. The converging ends of the wires G are united by means of a chain G², the links of which are adapted to engage with the sprockets of the wheel H.

To give a rotary motion to the shaft I, a ratchet-wheel L is secured upon said shaft, 55 and the sprocket-wheel H has two radial arms h, each projecting therefrom on the side adjacent to the wheel L, and to the outer ends of said arms are pivoted the pawls h², so as to ride over the ratchet-wheel, and springs h³ 60 pressing upon said pawls to retain the latter in engagement with the ratchet-wheel. To give continuous motion to the shaft I, a fly-wheel M is secured upon a counter-shaft M², carried in bearings upon stanchions K². For 65 this purpose a cog-wheel N is mounted upon the shaft I, and said wheel is made to mesh with a pinion n upon the counter-shaft M², and the momentum of the fly-wheel will help to transform the intermittent motion of the 70 pawls upon the ratchet-wheel L into continuous rotary motion. Upon the shaft I is also mounted a belt-pulley P, carrying a belt p, by which motion can be given to the beaters of a churn, of a washing-machine, or other 75 mechanism.

To retain the wires G under tension, and also to prevent sudden jerks in starting or reversing the intermittent pull upon each wire alternately, a three-coiled wire spring-coupler 80 Q is placed upon one of the wires, the central coil being around a pin q, connected with the double lever E, and the frame q², carrying said springs, is attached to the wire G.

We are aware that oscillating beams and 85 wires, or connecting-rods uniting them, have been used to transmit power from a distance to operate various mechanisms; but their mode of connection with the driven shaft differs from ours.

Having now fully described our invention, we claim—

The combination of a vertically-reciprocating rod, its pitman, the double lever E, having a T-shaped central arm, and wires d, uniting 95 said central arm to the ends of the double

lever, the wires G, a spring-coupler Q, mounted upon one of said wires, the sprocket-chain G², uniting said wires, the sprocket-wheel H, having two radial arms h, and pawls h², pivoted 5 to said arms, the ratchet-wheel L, its shaft, and the gear N upon said shaft, with the counter-shaft M², its pinion n, and fly-wheel M, substantially as described.

In testimony whereof we affix our signatures in presence of two witnesses.

JOHN M. MCNEAL.
WILLIAM F. RUNNELLS.
